DESIGN FOR A PAIR OF GOGGLES

Frank R. Ernst, Wood-Ridge, N. J., assignor to Columbia Protekosit Co., Incorporated, Carl-stadt Township, Bergen County, N. J., a corporation of New Jersey

Application April 10, 1940, Serial No. 91,566

Term of patent 3½ years

To all whom it may concern:

Be it known that I, Frank R. Ernst, a citizen of the United States and resident of Wood-Ridge, in the county of Bergen and State of New Jersey,
have invented a new, original, and ornamental Design for a Pair of Goggles, of which the following is a specification, reference being had to the accompanying drawing, forming a part thereof, and in which:

Fig. 1 is a perspective view of a pair of goggles embodying my new design; and

Fig. 2 is a top plan view of the pair of goggles shown in Fig. 1.

I claim:

The ornamental design for a pair of goggles,
substantially as shown.

FRANK R. ERNST.
